UNITED STATES PATENT OFFICE.

GEORGE N. CRAWFORD, OF CHICAGO, ILLINOIS, ASSIGNOR TO FREDERICK C. AUSTIN,
OF CHICAGO, ILLINOIS.

LIFTING APPARATUS.

1,384,051.

Specification of Letters Patent. Patented July 12, 1921.

Application filed July 2, 1917. Serial No. 178,137.

To all whom it may concern:

Be it known that I, GEORGE N. CRAWFORD, a citizen of the United States of America, and resident of Chicago, Cook county, Illinois, have invented a certain new and useful Improvement in Lifting Apparatus, of which the following is a specification.

My invention relates to apparatus of that kind in which a swinging boom is employed, such as those on excavating machines, and especially those in which a drag-line-scraper or bucket is suspended from the end of the swinging boom, whereby a load of dirt or other material can be carried upward and swung around and dumped in the desired place.

Generally stated, the object of my invention is to provide a novel and improved construction whereby the raising and lowering of the boom may be controlled through the medium of a single hand-lever or other similar device, so that the boom and its load may be raised and lowered at the will of the operator.

It is also an object to provide certain details and features of construction and combinations tending to increase the general efficiency and desirability of a boom-controlling or raising-and-lowering mechanism of this particular character.

To the foregoing and other useful ends, my invention consists in matters hereinafter set forth and claimed.

In the accompanying drawings:—

Figure 1 is a side elevation of a drag-line scraper-excavating machine embodying the principles of my invention, showing one end thereof broken away for convenience of illustration.

Fig. 2 is an enlarged top plan view of the winding - drum - mechanism and hand - lever therefor by which the raising and lowering of the boom is controlled at will.

Fig. 3 is a side elevation of said mechanism.

As thus illustrated, my invention comprises a frame or body A, of any suitable character, mounted upon a turn-table B, whereby the body is adapted to swing about the vertical axis provided by the pivot b, the body being supported by wheels a on said turn-table. The turn-table, it will be understood, is supported at one end of the machine by the traction-devices C which, as shown, are in the nature of caterpillars, and by wheels or other supporting elements at

the other end of the body, or by similar traction-devices. A boom D is pivoted at d upon the end of the body, so that the outer end of the boom may swing up and down about a transverse axis at its lower end. The hoisting cable or line E is wound upon a drum F, mounted on the body to rotate in bearings f, and is supported by a sheave G at the outer end of the boom, the end-portion of the line being looped around the swinging sheave g and then brought upward and fastened at 1 to the outer end-portion of the boom. The sheave g is carried by a block 2 which is pivoted at 3 to the upper end of the bail 4 of the drag-line-bucket or scraper H, which latter is of any suitable character and provided with a drag-line h that leads around the sheave 5 at the base of the boom, and which extends to the smaller diameter 6 of the previously mentioned winding drum. This line h leads around a sheave 7 on the upper portion of the bail 4 and then downward to its point of attachment 8 on the front end of the bucket. A hitch 9 extends between the front end of the bucket and the clamp 10 on said line, and the bucket is provided with stops 11 against which the bail 4 will bear while the bucket is being tilted, at which time the hitch 9 sustains the draft or pull on the drag-line, the hoist-line E being slack. When the bucket is hoisted with the load therein, a pull is maintained on the line h to keep the bucket in carrying position, but after the bucket is raised, and as soon as the pull on the drag-line h is relaxed, the front end of the bucket will then tilt downward, inasmuch as the portion of the line h which extends around the sheave 7 will not be taut. The pivotal points 12 for the bail 4, on the sides of the bucket, are nearer the rear end of the bucket, so that as soon as the pull on the line h is reversed, so that the line becomes slack, the heavy front end of the bucket then tilts downward and discharges the load.

The boom D is supported by a rod 13 having sheaves 14 for the line 15 which extends around the sheaves 16 on the upper portion of the super-structure 17 of the body. Said line 15 has one end fastened at 18 to the boom, then passes over one of the sheaves 16 and out and around one of the sheaves 14, then back and around another sheave 16, then outward and around another sheave 14, then back and around another sheave 16, then outward and around another

sheave 14, and then back and around another sheave 16, and back to the winding drum I on the body, which drum is supported on a shaft *i* in bearings on the body-frame. The 5 shaft *f* has a relatively large gear-wheel 19 which engages the pinion 20 on the shaft *i*, whereby the two shafts rotate in opposite directions. The shaft *i* is provided with a clutch-device J, of any suitable character, 10 such as an ordinary friction or band clutch, for connecting the shaft with the drum I, when the raising-and-lowering line 15 is to be wound thereon, and for releasing said drum when this line is to be paid out or 15 unwound. A rock-shaft K is mounted on the body-frame, parallel with the shaft *i*, adjacent thereto, and provided with an arm *k* which is connected by a rod 21 with the bell-crank 22, which latter is suitably sup- 20 ported on the body-frame to oscillate about a vertical axis. The clutch J is controlled by a fork 23 which is pivoted on the body-frame at 24, and which has its lower end connected by a rod 25 with the other end- 25 portion of the bell-crank 22, whereby the rocking of the shaft K, by means of the hand-lever 26 at one end thereof, will tighten and release said clutch. This shaft K is also provided with an arm 27 which is keyed thereon, and which has a connection 28 with one end of the band-brake L which is applied to the other end of the drum I, where- 30 by the drum can be released from the shaft *i* and thereafter held against rotation by the 35 unwinding of the line 15 under the weight of the boom. The other end of this band-brake L is anchored at *l*, upon any suitable part of the body-frame.

When the hand-lever 26 is in the position 40 shown in full lines in Fig. 3, the clutch J is closed, so that the drum I is locked to the shaft *i*, and the band-brake L is released. When the hand-lever is thrown into the position shown in dotted lines at 29, both the 45 clutch and the brake are then open or inoperative, and the weight of the boom will unwind the line 15 from the drum. When the hand-lever is pulled into the position shown in dotted lines at 30, the clutch is 50 still open, but the band-brake is closed or tightened on the drum, so that the latter is held against rotation. Consequently, by moving the hand-lever from the position 30 toward the position 29, the band-brake will 55 be slightly released to allow the boom D to swing downward by gravity, under the full control of the operator, and as soon as the boom is in the desired position the lever is then pulled back into the position at 30 to 60 tighten the brake on the drum. When it is desired to again lift the boom with its load, the hand-lever is pushed into the position shown in full lines in Fig. 3, which closes the clutch, leaving the band-brake released. 65 The shaft *i*, it will be understood, is rotat-

ing constantly, being connected through the gearing 19 and 20, and other gearing of any suitable character, with an engine or other source of motive power mounted on the body. The rotation of this shaft *i* is, of course, in a direction to wind the line 15 on the drum I, when the clutch J is operated, so that the drum is keyed to the shaft, and the drum and shaft rotated in opposite directions when this line is unwound to 75 permit downward movement of the boom.

It will be understood, of course, that the drum F, or drums, on the shaft *f*, are also driven from said source of power, and controlled by clutches or brakes in any suitable or desired manner.

With the foregoing construction, it will be seen that the raising and lowering of the boom D is controlled by the single hand-lever 26, so that the boom and its load can 85 be raised and lowered at will by simply manipulating this single hand-lever. Thus, the boom can be raised and lowered and controlled like that of a crane, when crane service is desired, and this advantageous 90 control is obtained without reversing the engine or motor from which the power is derived. Any suitable means can be employed for holding the lever 26 in one or more of its different positions. For example, a plate M can be mounted on the body-frame to engage the lever, to hold the latter in the position indicated at 30, and a longer plate N can be secured to the edge of the 95 body-frame to coöperate with the plate M to hold the lever in the position indicated at 29, but not in the position which the lever must assume to close the clutch. It will be understood that said lever 26 can 100 be flexible enough to permit slight outward movement thereof, to disengage it from said plates, and so that it may be swung freely back and forth by the operator. The clutch J, being a friction clutch or band clutch, 105 operates gradually, so to speak, and does not suddenly lock the drum I to the shaft *i*, but provides a frictional connection between the drum and the shaft, so that some slippage takes place before the drum is 110 finally connected to rotate in unison with the shaft, and in unison with the movable clutch section *j* which is splined on the shaft. The brake L operates in a similar manner, so that the frictional breaking action is gradual, and in this way the drum I is subject to frictional action by the clutch to rotate the drum in a direction to raise the boom, and to frictional action by the brake to hold the boom in raised position, and with the combination of these two frictional devices the drum is under full control and can be rotated in either direction at the will of the operator, or held against rotation, depending upon the character of 115 the work to be done. A ratchet O can be 120

125 130 135

applied to one end of the drum I, to lock it against reverse rotation after the boom has been raised, if such is desirable or necessary, it being understood that this ratchet 5 can be provided with a dog or pawl which can be manipulated by hand to throw it into or out of action when desired. With this combination of friction brake and friction clutch, under the control of a single lever, 10 the lifting apparatus can be used in different ways, for different purposes, and has the essential requirements of a crane. The raising of the boom will bring the load closer to the body-frame of the machine, 15 while the lowering of the boom will swing the load away from the machine, and with the arrangement whereby the boom is adapted to swing around sidewise, it is evident that a load can be picked up at any 20 point and thereafter put down at any other point within the range of movement of the boom.

What I claim as my invention is:—

1. In lifting apparatus, instrumentalities 25 to carry the load, a line to raise and lower said instrumentalities, a winding drum for said line, a clutch for rotating said drum to raise the load, a brake for said drum, means to swing the load sidewise, a single lever 30 connected to control both the clutch and the brake, so that the load may be raised or lowered at will by operation of said single lever, a shaft on which said drum and clutch and brake are supported, the clutch being 35 operable to connect the drum to the shaft by movement of said lever in one direction, and adapted to release the drum when said lever is moved in the opposite direction to apply said brake, whereby the drum is rotatable with the shaft to raise said instrumentalities and rotatable in the opposite direction on the shaft under control of said 40 brake to lower the boom.

2. In lifting apparatus, instrumentalities 45 to carry the load, a line to raise and lower said instrumentalities, a winding drum for said line, a clutch for rotating said drum to raise the load, a brake for said drum, means to swing the load sidewise, a single 50 lever connected to control both the clutch and the brake, so that the load may be raised or lowered at will by operation of said single lever, the connection from said lever to the clutch and brake including a 55 rock-shaft arranged parallel with the drum and having one connection with the clutch and a separate connection with the brake.

3. A structure as specified in claim 1, including a rock shaft connected separately 60 to the clutch and drum and forming a support for said lever.

4. The combination, in an excavator, of 65 instrumentalities to carry the load, a line to raise and lower said instrumentalities, a winding drum for said line, a clutch for

rotating said drum to raise the load, a brake for said drum, means to swing the load sidewise, a single lever connected to control both the clutch and the brake, so that the load may be raised or lowered at will by 70 operation of said single lever, a shaft extending through the drum and clutch, and means to rotate said shaft.

5. In hoisting apparatus, the combination 75 of a winding drum, instrumentalities operated by said drum, a friction brake associated with said drum, a clutch associated with said drum, a horizontal shaft for said drum, said clutch controlling the transmission of power from the shaft to the drum, 80 a horizontal rock-shaft arranged parallel with said drum-shaft, a connection from said rock-shaft to said friction brake, a separate connection from said rock-shaft to said clutch, whereby operation of the rock-shaft in one direction will open the clutch and tighten the friction brake while operation of the rock-shaft in the opposite direction will loosen the friction brake and close the clutch, manually controlled means 85 for operating said rock-shaft in either direction to control said instrumentalities, a bucket connected to be raised and lowered by said drum, and means to swing the bucket sidewise. 95

6. A hoisting apparatus as specified in claim 5, said means comprising a single hand-lever secured to said rock-shaft, the clutch connection being disposed between said hand-lever and the other connection to 100 the brake.

7. A hoisting apparatus as specified in claim 5, said manually controlled means comprising a hand-lever, and locking means to engage the hand-lever, the said hand-lever having one position in which it is locked against movement in either direction, and another position in which it is locked against movement in one direction, and another position in which it is free to move 110 in either direction. 105

8. In an excavating machine, the combination 115 of a body mounted on a turn-table, a boom pivoted on said body to swing up and down, devices including a winding drum to raise and lower said boom at will, a drag line bucket, a hoist line to support the bucket on the boom, a drag line by which to pull the bucket toward the excavator body, means to operate said drum, and means to operate said hoist line and drag-line, said devices including a single hand lever having a plurality of positions and a 120 brake and a clutch both of which are controlled thereby to control the raising and lowering of the boom at will. 125

Signed by me at Chicago, Illinois, this 16th day of June, 1917.

GEORGE N. CRAWFORD.
